DESIGN FOR A PRECIOUS OR SEMIPRECIOUS OR SYNTHETIC STONE

Armand Bayardi, New York, N. Y., assignor of two-fifths to Bayardi Brothers, Inc., New York, N. Y., a corporation of New York, two-fifths to Larter & Sons, Newark, N. J., a corporation of New Jersey, and one-fifth to George A. Schuetz, Maplewood, N. J.

Application October 10, 1933, Serial No. 49,440

Term of patent 14 years

To all whom it may concern:

Be it known that I, ARMAND BAYARDI, a citizen of the United States, and a resident of New York, in the county of Queens and State of New York, have invented a new, original, and ornamental Design for Precious or Semiprecious or Synthetic Stone, of which the following is a specification, reference being had to the accompanying drawing, forming part thereof.

Figure 1 is a top plan view of a cut stone showing my new design.

Figure 2 is a side elevation thereof,
Figure 3 is an elevation of one end of the jewel,
and

Figure 4 is an end elevation of the other end.
I claim:

The ornamental design for a precious or semiprecious or synthetic stone, as shown.

ARMAND BAYARDI.
